WEED EXTERMINATOR

Filed March 8, 1928

UNITED STATES PATENT OFFICE

JAMES J. SULLIVAN, OF ARAPAHOE COUNTY, COLORADO

WEED EXTERMINATOR

Application filed March 8, 1928. Serial No. 260,224.

This invention relates to devices for applying liquids to weeds for the purpose of killing weeds and has for objects to provide a device of the class described which will be simple and effective in operation, in handy and convenient form for use and which will carry a substantial supply of the liquid to be used and which shall embody means for readily injecting such liquid into the root of the plant and also means for preventing plugging of the injecting device.

With the foregoing and other objects in view as will more fully appear from the following specifications and claims, the invention comprises certain novel constructions, combinations and arrangements of parts as hereinafter more fully described and claimed and as illustrated in the accompanying drawing in which will be characters of reference 20 indicating corresponding parts throughout the various views and in which

Figure I is an illustration of the complete device.

Figure II is a central, longitudinal section 25 thereof.

Figure III is a cross section on line A—A, Figure I.

Figure IV is a detailed central sectional view of the lower end of the device, illustrating the injecting structure with the plunger down in position to close the opening in the injector point.

Figure V is a view corresponding to Figure IV except that the plunger is shown in raised position, thus opening the injector point to permit the flow of the liquid.

The device consists of a barrel 1 of any suitable diameter and preferably of length 40 a little shorter than an ordinary walking cane. At its lower end, the barrel is provided with a cap 2 which may be threaded thereto as at 3, which cap is provided with a hollow injecting tube 4 tapered to a point as at 5. The tube 4 projects upwardly into the barrel 1 and the portion thereof within the barrel is provided with a plurality of slots or orifices 6 affording communication between the interior of the tube 4 and the interior of the 50 barrel 1 and also constituting runways for

the lugs of the plunger as hereafter described.

At the top the barrel is provided with a handle 7 which may be threaded to the barrel as at 8. Within the top of the barrel there is 55 provided a rest 9 with an orifice therein, located in alignment with the tube 4 and through this orifice and extending downward into the tube 4 is a plunger 10 having a head 11 normally resting upon the rest 9 and a tapered or beveled point 12 adapted, when the plunger is at its lowermost position, to align with the tapered point of and smoothly close the opening in the lower end of the tube 4 whereby, when the plunger is 60 in said lowermost position, the tube and plunger together will form a solid point for making a hole in the root of the plant to which the liquid is to be applied.

The plunger is provided with lugs 13 sliding in slots 6 for preventing revolution of the plunger and for maintaining the alignment of the point of the plunger with the point of the tube 4 when the plunger is at its lowest position.

A seat 14 is mounted upon the plunger and a compression spring 15 encircles the plunger between the seat 14 and the rest 9. The head 11 is provided with suitable finger engaging means 16 for lifting the plunger 80 against the compression of the spring 15 with one finger of the hand which engages the handle 7.

A protective cap 17 may be provided for the lower end of the tube 4, if desired.

In operation the plunger is allowed to remain at its lowermost position, as shown in Figure II and the liquid to be used upon the plants is poured into the top of the barrel around the seat 9. The device is carried in 90 one hand, by the handle 7, and being approximately the length of an ordinary walking-stick, the operator may remain substantially upright carrying the device and when it is desired to operate the device, the point 5 is inserted into the root of the plant. The plunger is thereupon lifted by means of the ring 16, thus opening the slot 6 as clearly indicated in Figure V, and allowing the liquid 100 to flow from the barrel through the slots into

the tube 4 and thence into the root of the plant whereupon the ring 16 is released and the spring 15 shoots the plunger down to its lowermost position, forcing the liquid out through the point of the nozzle, closing the slot 6 and preventing further flow of the liquid and also closing the open lower end of the nozzle and forming a smooth, solid point for insertion into the root of the next plant.

10 It will be obvious that this construction permits the injection into the root of the plant of any desired quantity of the liquid up to capacity of the passage in the nozzle and at the same time prevents plugging with 15 dirt or other material of the hollow point used to accomplish the injection.

In most cases a drop or two of the liquid will be sufficient so that after the point is injected into the root of the plant, the plunger 20 will be lifted and allowed to snap back immediately, sufficient of the liquid passing into the interior of the tube 4 during an almost instantaneous opening and closing of the slots 6 by such lifting and release of the 25 plunger.

25 In this way a large quantity of the exterminating liquid may be carried and may be injected into the roots of the plants without bending or other inconvenience to the 30 operator.

Many changes in details of construction 35 will be obvious to those skilled in the art and many such changes can be made without departing from the spirit and the scope of these specifications and the appended claims.

I claim—

1. In a weed exterminator, a liquid-carrying barrel, a bevel pointed nozzle leading from one end thereof, a plunger slidably 40 mounted within and adapted to close the nozzle and having a point beveled to correspond with the point of the nozzle whereby, when the nozzle is closed by the plunger, the walls of the nozzle point combined with 45 said plunger point form a substantially smooth and solid point, and means for preventing revolution of the plunger relative to the nozzle.

2. In a weed exterminator, a liquid-carrying barrel, a pointed nozzle leading from one end thereof, a plunger slidably mounted within the nozzle and having a point corresponding in shape with the point of the nozzle whereby, when the nozzle is closed by 55 the plunger, the walls of the nozzle point combined with said plunger point form a substantially smooth and solid point, lugs carried by the plunger and slots in the walls of the nozzle for said lugs and for permitting 60 liquid to flow from the barrel into the nozzle.

3. In a weed exterminator having a liquid-carrying barrel, a tube tapered to a point below the barrel and extending upwardly into the barrel, a plunger having a sliding fit 65 within the tube and a point shaped to smooth-

ly close the lower end of the tube, and orifices in the walls of the tube adapted to be opened by retraction of the lower end of the plunger to permit liquid to flow from the barrel into the tube below the end of the plunger.

4. In a weed exterminator having a liquid-carrying barrel, with a tube positioned in the lower end of the barrel and having a beveled point extending therebelow, a plunger in the tube and having a beveled point adapted to smoothly close the end of the tube, and means to permit reciprocation, but to prevent rotation, of the plunger.

5. In a weed exterminator having a liquid-carrying barrel and a ground piercing tube with a plunger slidably mounted therein and adapted to open and close the tube, in combination, a beveled point on the tube, a corresponding beveled point on the plunger, means for reciprocating the plunger and alternately admitting liquid from the barrel to the tube below the plunger and smoothly closing the lower end of the tube and means for preventing rotation of the plunger.

In testimony whereof, I affix my signature.

JAMES J. SULLIVAN.
